UNITED STATES PATENT OFFICE.

LOUIS RORHEIMER, OF CLEVELAND, OHIO, ASSIGNOR TO H. G. FETTEROLF CO., OF PHILADELPHIA, PENNSYLVANIA, A CORPORATION OF PENNSYLVANIA.

DESIGN FOR A CARPET, RUG, OR SIMILAR ARTICLE.

52,013.

Specification for Design.

Patented May 7, 1918.

Application filed December 8, 1917. Serial No. 206,351. Term of patent 3½ years.

To all whom it may concern:

Be it known that I, LOUIS RORHEIMER, a citizen of the United States, residing at Cleveland, in the county of Cuyahoga and State of Ohio, have invented and produced a new, original, and ornamental Design for Carpets, Rugs, or Similar Articles, of which the following is a specification, reference being had to the accompanying drawing, forming a part thereof.

The drawing is a view of a single unit of the design, it being understood that any number of repeats may be employed, as indicated, to produce an entire fabric.

The design unit comprises an approxi-

mately square figure made up of approximately square corner blocks and smaller approximately square border blocks with conventional figures within the square. The solid black, as shown in the drawing, and the stippling represent contrasting colors, the solid black being intended to represent a darker color than the stippling.

I claim:

The ornamental design for a carpet, rug, or a similar article as shown and described.

LOUIS RORHEIMER.
